ARCHER'S GLOVE

Hicks Jones, Centerline, Mich.

Application October 28, 1957, Serial No. 48,252

Term of patent 14 years

(Cl. D3—11)

Fig. 1 is a top perspective view of an archer's glove showing my new design.

Fig. 2 is a bottom perspective view thereof.

I claim:

The ornamental design for an archer's glove, substantially as shown.
